UNITED STATES PATENT OFFICE.

CHARLES M. GREY, OF EAST ORANGE, NEW JERSEY.

ART OF DIE CASTING.

Application filed October 28, 1920. Serial No. 420,132.

To all whom it may concern:

Be it known that I, CHARLES M. GREY, a citizen of the United States, residing at East Orange, in the county of Essex and State of New Jersey, have invented certain new and useful Improvements Pertaining to the Art of Die Casting, of which the following is a specification.

This invention relates to the art of die casting and is directed, more particularly, to a novel method of manipulating the pressure pot to effect the charging thereof with fluid metal, the subsequent discharging of a portion of the metal into a die, and, thereafter, emptying the pot, when desirable, before recharging the same.

More specifically, the invention, in one of its main aspects, embodies the introduction of metal into a tiltable pressure pot by means of a vacuum. In practice, a pressure pot, preferably having a substantially U-shaped longitudinal cross section, is employed, and, upon tilting the pot, so as to position the same for introducing metal therein, the nose of the pot, i. e., the metal inlet to the pot, is submerged below the surface of the metal, and beneath the surface dross strata, whereupon a vacuum is produced in the pot with the result that the metal is drawn directly into the pot. The desired quantity of metal having been drawn into the pot, the pot is tilted upwardly, but the vacuum therein is turned off, i. e., broken, before the nose of the pot reaches the dross strata. When the vacuum is broken, the pot is vented to the atmosphere with the result that metal is flowing out of the pot while the nose is passing through the surface of the metal, and, particularly, when passing through the dross strata, thereby effectively precluding any dross or surface impurities from entering the pot.

In the preferred manner of practicing the invention, a very much larger quantity of metal is taken into the pot than is employed in the subsequent operations of casting, and before recharging the pot, the surplus metal may be allowed to flow out of the pot into the main bath of molten metal, the out-flow of metal being so arranged that it is occurring while the nose of the pot is being submerged into the bath, so that said out-flowing current precludes the inflow of slag.

In operating as above described, several important advantages result, among which may be mentioned the following. A large

charge of clean metal is expeditiously drawn into the pot; no dross can enter the pot, thereby assuring the purity of the metal; there is no accumulation or piling up of metal in the pot, and, further, the repeated emptying of the pot insures the uniformity of the metal, both in the main bath and in the pot.

The parts of the apparatus employed in practicing the present method are so co-ordinated in operation that during the righting, or return of the pot to its upstanding position, the surplus metal introduced into the pot is allowed to flow from the charging opening while such charging opening is passing through the surface strata of the molten metal bath, thereby obviating the slightest tendency of the surface dross to enter the pot.

Features of the invention, other than those adverted to, will be apparent from the hereinafter detailed description and claims, when read in conjunction with the accompanying drawings.

In the accompanying drawings, I have, for the purpose of illustration, shown one, and the preferred, form of apparatus wherein the method constituting the subject matter of the invention may be successfully practiced, but I wish it understood that the form of apparatus shown is for the purpose of illustration, only, and is not intended to be exclusive of other forms of apparatus which may be employed.

In the drawings, Figure 1 is a more or less diagrammatic showing of the apparatus; and,

Figures 2 to 6, inclusive, are diagrammatic illustrations of the various positions taken by the pressure pot at different times, during the operation of the apparatus.

Referring to the drawings, A indicates a melting pot containing a pool or bath of molten metal B, which forms the source of supply for the pressure pot C. The melting pot A is usually mounted in a suitable furnace of which it forms a part and is heated externally by any suitable means.

The pressure pot C may be of any one of several forms, but is here shown as substantially U-shaped in cross section. The pot is provided at one end with a discharge nozzle D, adapted to cooperate with the die (not shown) in such manner as to feed molten metal from the pot into the die, while the other end of the pot is connected, in any

suitable manner, preferably by a flexible tube E, to a system or piping by means of which the pot may be vented, pressure applied to the pot, or air exhausted therefrom.

- 5 The pot may be supported in any desired manner, but is here shown as pivotally mounted on a hanger F which is, in turn, mounted for sliding movement on two parallel guides, only one of which is shown and 10 is designated G. By this mounting, the pot may be slid on the guides G into casting position with reference to the die and away from casting position with reference thereto, and, because of the pivotal mounting of 15 the pot, it may, while in retracted position, be tilted to submerge the nozzle below the surface of the molten metal bath B, although the normal position of the pot is the up-standing position shown in Figure 1.
- 20 In the form of pot shown, the pot is charged through a charging opening d in the nozzle, though it may be otherwise charged, if desired.

For the purpose of illustration, I have 25 shown means for tilting the pot embodying a crank H, which is rigid with respect to the pot and is adapted when the pot is retracted to engage with either a fixed or movable member h, so that as the pot is retracted, the 30 crank H and member h will engage with one another and effect the tilting of the pot.

The piping system hereinbefore referred to as connected with the pressure pot C through the flexible tube E may differ from 35 the showing in the drawings without departing from the invention, and, in practice, several additional valves over those illustrated are usually employed, but for the purpose of illustration here, I have shown 40 a simplified form of arrangement by which the method may be readily understood. No endeavor will be made to describe the specific piping as this is largely a matter of convenience, but will simply describe the 45 five valves illustrated and explain their uses.

I is a vacuum valve, or the valve which controls the exhausting of air from the pressure pot. J is a vacuum relief valve, the function of which is to preclude the 50 building up of too great a vacuum. K is a pressure valve or the valve by means of which pressure is admitted to the pressure pot. L is a check valve and M a vent valve. The check valve L and the vent valve M are 55 included in the same branch of piping and together control the admission of air at atmospheric pressure into the system. In practice, the valves K and M are preferably manually operated, the valves I and L are 60 preferably controlled by the position of the pot, while the valve J is automatically controlled by the degree of vacuum and is normally closed unless an excess vacuum is built up, whereupon it automatically opens 65 and holds down the vacuum.

It may be here noted that, in practice, the valves K and M are coupled together, so that when the pressure pot is in casting position and pressure is turned into the pot, through an opening in the valve K, the vent 70 valve M will be closed, and, conversely, when the pressure is shut off, the vent valve will be opened. These valves may be operated automatically, but I preferably operate them manually, so that there will be no liability 75 of pressure being turned into the pot and the metal forced through the nozzle thereof until the operator of the machine has assured himself that the nozzle of the pot is in proper cooperative relation to the inlet of 80 the die. In this way, accidents due to burning of the operator or broadcast distribution of molten metal are obviated. These several features are, however, optional and the valves of the piping system may be operated 85 either mechanically or automatically as desired.

I will now explain the operation of the apparatus shown in the carrying out of the method of this invention, explaining the 90 several steps of the method and the various positions which the pressure pot and the several valves of the system partake during the operation of charging and discharging the pot.

Figure 1 shows the parts in the position which they take while the pot is being discharged, i. e., its contents being forced into the die. This is accomplished by the opening of the pressure valve K to admit pressure into the pot, while all the other valves in the system may be closed. The system should be sealed at this time, but as the vent valve is closed to accomplish this, the check 95 valve L may be opened.

At the conclusion of the discharging operation, the pressure valve K is closed and simultaneously the vent valve M is opened, so that the pot is vented and the metal which remains therein assumes a quiescent state in 100 the base of the pot. The pot is now slid upon the guides G to the retracted position shown in Figure 2, at which time, the crank H engages with the member h and the pot proceeds to tilt. During the tilting of the 105 pot from the position shown in Figure 2 to that shown in Figure 3, both the check valve L and the vent valve M will be open, while the vacuum valve I will be closed. The pot will be vented and will remain in this condition until it reaches the position shown in Figure 3, wherein the nozzle or charging opening d of the pot will have passed below the surface of the metal bath B and below the surface strata of said bath. During this 110 initial tilting movement of the pot, if there is any appreciable amount of metal left in the pot, it will flow from the nozzle and this flow will be accomplished during the passage of the nozzle through the surface strata of 115 120 125 130

the metal bath, thereby obviating the slightest tendency of the surface dross to flow into the pot during this initial tilting operation.

5 When the pot reaches the position shown in Figure 3, the check valve L will be closed, and the vacuum valve I opened with the result that air will be exhausted from the pot and molten metal will flow from the bath 10 through the charging opening d into the pot. The pot will continue to tilt, until it assumes the position shown in Figure 4, during which time, the valves will remain the same as in Figure 3 and the charging operation 15 of the pot will continue.

Figure 4 shows the pot tilted to the maximum and after reaching this maximum tilt, the pot will commence to right itself.

During the initial part of the righting operation, the charging of the pot may continue to assure that it is fully charged, but as the charging opening of the pot approaches the surface strata of the bath, and before it reaches the dross strata, the vacuum valve I is closed, and the check valve L is opened. The vent valve M has remained opened during the previous operations, so that at this time, the charging of the metal 20 will cease and the venting of the pot will take place. This occurs when the pot is in approximately the position shown in Figure 30 5.

As soon as the pot is vented the surplus metal which has been drawn into the pot 35 through the charging operation, commences to flow out of the charging opening, and continues to flow, while the charging opening of the pot is passing through the surface dross strata of the bath and for a time thereafter, 40 as shown in Figure 6 until through continued tilting of the pot, it assumes its upright position shown in Figure 2 with the valves in the condition shown in Figure 2.

While these operations have been occurring, the die has been prepared for the next casting operation, so that the pot may now be moved forward into cooperative relation with the die and in position for the next casting operation. The vent valve M is 50 then closed and the pressure valve K opened to admit pressure into the pot for the purpose of partially discharging the contents of said pot through the forcing of the metal therein into the die. The parts of the apparatus are at this time, as shown in Figure 1, one complete operation of casting having been accomplished.

The series of operations described are repeated for each casting, and, in practice, are 60 accomplished with more or less rapidity and in relatively continuous sequence.

It will be apparent from the foregoing description that the entrance of surplus dross or impurities, which stratify on the 65 surface of the molten metal bath, into the

pressure pot, is entirely obviated. I have referred to the flowing of metal through the nozzle during the initial tilting of the pot and this will occur if there is any appreciable amount of metal left in the pot after 70 the previous casting operation, but even though this does not occur, the surface metal of the bath will not flow into the pot during this time, for the reason that the vacuum is not turned on until the nozzle is well below 75 the surface of the bath. During the righting of the pot, however, molten metal will flow from the nozzle during its passage through the surface strata of the bath, so that when the pot is fully righted and 80 ready for casting, it will be entirely free from surface impurities, dross or slag.

It will be manifest that applicant's method is not limited to the complete or detailed operations hereinbefore described, but that the invention is as broad as is commensurate with the appended claims. Moreover, the apparatus, described, both specifically and generically, forms part of applicant's invention. 90

Having thus fully described the invention, what I claim as new and desire to secure by Letters Patent is:

1. In the art of die casting, the method of charging a casting pot which consists in tilting the pot to bring its charging opening below the surface dross strata of a pool of molten metal, precluding the entrance of surface dross into the pot during such tilting movement, drawing metal into the pot 100 solely from below the surface dross strata, and then righting the pot, and precluding the entrance of dross into the pot during the righting thereof. 95

2. In the art of die casting, the method of charging a casting pot which consists in introducing its charging opening below the surface dross strata of a pool of molten metal while precluding the flow of dross into the pot, then drawing dross-free metal into 110 the pot by means of a vacuum, and thereafter removing the charging opening of the pot from the pool and precluding the entrance of dross into the pot while said outlet is passing through the surface dross 115 strata.

3. In the art of die casting, the method of introducing molten metal into a tilttable pressure pot which consists in submerging the metal inlet to the pot below the surface of 120 the bath of metal, then drawing metal into the pot by means of a vacuum created therein, then tilting the pot so as to elevate the metal inlet to the pot above the surface of the metal bath but breaking the vacuum in 125 the pot before it reaches the superficial dross strata.

4. In the art of die casting, the method of introducing molten metal into a tilttable pressure pot which consists in submerging the 130

metal inlet to the pot below the surface of the bath of metal, then drawing metal into the pot by means of a vacuum created therein, then tilting the pot so as to elevate the metal inlet to the pot above the surface of the metal bath but breaking the vacuum in the pot before it reaches the superficial dross strata, then utilizing a portion of the metal in the pot for casting, then again tilting the pot so that its metal inlet becomes submerged in the metal bath, but causing metal to flow out of said inlet during its downward passage through the dross strata on the bath, whereby slag or dross is precluded from entering the pot.

5. In the art of die casting, the method of supplying molten metal to a tiltable casting pot, which consists in moving the pot to submerge its charging opening into a body of molten metal at a point therein below the surface dross strata of the body of molten metal, then producing a partial vacuum in the pot so as to induce the flow of molten metal into the pot, thereafter returning the pot to initial position and breaking the partial vacuum in the pot before the charging inlet thereof reaches the surface dross strata of the molten metal body, whereby only pure metal enters the pot.

30 6. In the art of die casting, the method of supplying molten metal to a tiltable casting pot which consists in tilting the pot so that its metal inlet is submerged below the surface dross strata of a molten metal bath, precluding the charging of the pot until its inlet has passed below the surface dross strata of the bath, and producing a partial vacuum in the pot while its inlet is below the surface dross strata to effect a flow of dross-free metal into the pot, whereby the pot is charged with dross-free metal only.

7. In the art of die casting, the method of supplying dross-free metal to a tiltable casting pot, which consists in tilting the pot to bring the charging opening thereof below the surface dross strata of a molten metal bath, effecting the flow of metal into the pot by means of a vacuum, while the charging opening thereof is below the surface dross strata, and causing a portion of the metal within the pot to flow from the charging opening thereof during the passage of such opening through the surface dross strata during the righting of the pot.

8. In the art of die casting, the method of supplying dross-free metal to a tiltable casting pot, which consists in tilting the pot to bring the charging opening thereof below the surface of a molten metal bath and causing metal to flow out of the pot during its downward passage through the dross strata on the bath, producing a partial vacuum in the pot after its charging opening is passed below the surface dross strata of the molten metal bath to induce the flow of molten metal into the pot, maintaining the partial vacuum in the pot for a sufficient time to effect the charging of the pot above its normal casting capacity, then returning the pot to initial position and breaking the vacuum before the charging opening of the pot reaches the surface dross strata of the molten metal bath, whereby a part of the contents of the pot is pouring from the charging opening thereof during its upward passage through the surface dross strata of the bath for the purpose of precluding the entrance of surface dross into the pot.

In testimony whereof, I have signed my name to this specification.

CHARLES M. GREY.
